Primary Examiner — Dominic Simone(74) *Attorney, Agent, or Firm* — Terence P. O'Brien(57) **CLAIM**

I claim the ornamental design for a portion of a side of a footwear article, as shown and described.

DESCRIPTION

The sole FIGURE is a side elevation view of a portion of a side of a footwear article.

The ornamental design that is claimed is shown in solid lines in the drawings. The broken lines shown in FIG. 1 are included for the purpose of illustrating environmental elements only and form no part of the claimed design.
